No. 56

Barber & Hoffman's designs for ornamenting Stones
Patented July 10, 1846.
No. 56

Des. 56

Robert Barber & Michael Hoffman, Bridgetown, N. J.

Letters Patent (Design No. 56) dated 10th July 1841. registered
May 18th 1840

The Schedule referred to in these Letters Patent and making
part of the same.

To all whom it may concern:

Be it known that we Robert

Barber, and Michael Hoffman, of Bridgeton, in the County of Cumberland, and
State of New Jersey, have invented or produced a new design or figure to be used
on stoves, and we do hereby declare the following to be a full and exact description
of the same, reference being had to the accompanying drawing making a part
of this specification. The composition of our design is as follows - the ends a, b
thereof resemble somewhat what is generally known as the "fleur de lis" - these
are connected by a combination of scroll work, surrounding and enclosing
a central ornament c, as represented in the accompanying drawing -

What we claim as our invention and desire to receive by Letters
Patent, is the ornamental figure or design for stoves, substantially as
herein set forth, and represented in the accompanying drawings.

Witness,
